AUTOMATIC PHONOGRAPH

Elmer O. Thompson, Grasmere, N. Y., assignor to
Philco Radio and Television Corporation, Philadelphia, Pa., a corporation of Delaware

Application November 14, 1940, Serial No. 365,708

2 Claims. (Cl. 192—124)

This invention relates to automatic phonographs of the type embodying a trip mechanism responsive to the rate of movement of the pick-up or reproducer over the record being reproduced. Such a trip mechanism is adapted to operate at the end of a record when the pick-up stylus engages a special groove having a greater pitch than the grooves in the main portion of the recording.

The trip mechanisms of this character which have been employed heretofore have been objectionable in that they may operate at the beginning of a record when the pick-up is moved laterally to place the stylus in the initial grooves of a record. The undesired operation of the trip mechanism in such instances is a source of annoyance since it causes the recording to be reproduced by the phonograph without being reproduced.

The principal object of the present invention is to provide an improved automatic phonograph mechanism which eliminates this objection of prior devices.

A more specific object of the invention is to provide in combination with a speed-responsive trip mechanism a novel means for preventing operation of the trip mechanism during the initial part of the reproduction of a record.

The invention may be clearly understood by reference to the preferred form thereof illustrated in the accompanying drawings, in which:

Fig. 1 is a perspective view illustrating the parts of the phonograph with which the invention is concerned;

Fig. 2 is an elevational view of the mechanism; and

Fig. 3 is a perspective view taken from a different angle to show the tone arm lifting device.

The automatic phonograph illustrated comprises the usual turntable 1 for supporting one or more sound records 2 and having the usual central spindle 3, driven by suitable means (not shown) preferably taking the form of an electric motor and reduction gearing. The tone-arm 4 is pivotally mounted in cooperative relation with the turntable by means of the pivotal mounting designated generally by reference character 5. The tone-arm is also pivotally connected to its support 5 at the upper end thereof for raising and lowering movement. Thus as is customary, the tone-arm is adapted to be raised or lowered and is also adapted to move laterally over a record when in lowered position. Both the turntable and the tone-arm 4 are mounted upon a common supporting table 6.

The tone-arm carries a suitable pick-up or reproducer which includes the needle or stylus 7. The pick-up is adapted to translate the undulations of the record grooves into corresponding electrical currents which are supplied to an amplifier and thence to a loud-speaker, as is well understood.

As illustrated in Fig. 3, the tone-arm 4 is adapted to be raised from the record 2 by means of a raising and lowering device 8 which is carried by the rotatable support 5. The device 8 comprises a member 9 pivotally attached to support 5 at 10. The member 9, in turn, carries a second member 11 which is pivotally attached to member 9 by means of the pivot pin 12. The member 11 has a downwardly-extending actuating arm 13 and another extending arm 14 to which a lift member 15 is pivotally attached at 16. The lift member 15 carries at its upper end a rod 17 whose upper end is adapted to engage the tone-arm. The lift assembly comprising member 15 and rod 17 extends through an opening 18 in the supporting table 6 to permit movement of the lift mechanism as the tone-arm support 5 rotates.

The lifting device 8 is actuated by means of a pivoted arm 19 whose operation will be described later. For the present, it suffices to state that when the member 11 is actuated by arm 19 in a counter-clockwise direction, as viewed in Fig. 3, the lift member 15 is raised, bringing the upper end of rod 17 into engagement with the tone-arm. Continued upward movement of the lift-arm 15 causes the tone-arm 4 to be lifted off of the record 2. In the meantime, however, the weight of the tone-arm acts to rotate the entire lifting mechanism about the main pivot 10, thereby to initiate operation of a means for moving the raised tone-arm so as to condition it for repeated playing of the record or the playing of a succeeding record. The present invention is not directly concerned with this latter means and for the present purpose a brief description thereof will suffice. The member 9 has an extending arm 20 on the end of which there is provided a cam follower 21 which is adapted to seat in an eccentric cam groove provided in the upper face of a disk 22 which is geared to the turntable shaft by means of the gear 23 on the disk, gear 24 on the turntable shaft, and an intermediate gear 25. The cam groove acting through arm 20 serves to rotate the tone-arm support 5 thereby rotating the tone-arm about its vertical pivot. Since this mechanism for rotating the tone-arm through an

arc when it is in raised position is well known and since the present invention is not directly concerned with it, it is unnecessary to illustrate or describe the said mechanism in further detail. Hence it has been deemed unnecessary to illustrate the cam groove in the upper surface of disk 22.

The present invention is concerned, however, with an additional function of the rotating disk 22 which results from spaced projections 26 on the underside of the peripheral portion of the disk. The purpose of these projections will be described later.

Referring now to Figs. 1 and 2, the arm 19 is shaped as illustrated and is pivoted at 27 to a supporting bracket 28 carried by the supporting table 6. The free end of arm 19 is curved as illustrated and is adapted to engage and actuate the tone-arm lifting device as shown in Fig. 3. The arm 19 is adapted to be actuated by a cam 29 carried by the rotating disk 22. The cam actuation of arm 19 is effected by means of a pivoted cam follower 30 on the said arm. The arm 19 has turned-up lugs 31 and 32 which serve as stops for the element 30 which is normally maintained against stop 32 by means of spring 33 secured at one end to a lug 34 on element 30 and at its other end to a lug 35 on arm 19. The arm 19 is urged toward operative position by a spring 36 secured at one end to the lug 35 and at its opposite end to a lug 37 on bracket 28. Normally, however, the arm 19 is latched in inoperative position against the action of spring 36 by a latch member 38 which is pivoted at 39 to the supporting bracket 28. The latch member has a hook-like end which engages a small knob 40 on arm 19. The latch member 38 is urged to latching position by spring 41, one end of which is anchored to the stationary support or bracket 28. When the arm 19 is latched in inoperative position as shown in Fig. 1, the element 30 is out of the path of cam 29 and, therefore, the cam is free to rotate without actuating arm 19.

The latch member 38 is adapted to be actuated by means responsive to the rate of movement of the tone-arm over a record which will now be described. On the tone-arm support 5, there is mounted a clutch member 42 which, together with a second clutch member 43, forms a friction clutch. The two clutch members 42 and 43 may take the form of clutch disks having frictionally-engaging faces, as will be well understood. The lower clutch member 43 is carried by a sleeve 44 which is slidably mounted on the rotatable tone-arm shaft 45. A spring 46 is arranged to maintain the clutch member 43 in engagement with the upper clutch member 42. This spring is seated in a retaining disk or washer 47 loosely mounted on the shaft 45 and adjustable to a desired position by means of adjusting nuts 48 and a screw 49 secured to the lower end of shaft 45.

The lower clutch member 43 has an extending arm 50 at the end of which there are turned-up elements 51 and 52 which are connected at their upper ends by means of a screw 53 and a coil spring 54 thereon. The element 51 constitutes a latch-tripping member and it is disposed adjacent to a shoulder 55 on the latch member 38. By means of the screw 53 and associated spring 54, the position of element 51 may be slightly adjusted in relation to the shoulder 55. It will be seen that rotation of arm 50 through clutch 42-43, as the tone-arm moves inward over a record, will tend to bring the latch-tripping element 51 into engagement with the shoulder 55.

The latch-tripping mechanism further comprises a pivoted bracket 56 which is pivotally mounted on a stationary bracket 57 carried by the support 28. The pivoted bracket 56 comprises a plurality of superposed arms 58, 59 and 60 which are riveted together at one end and which have their opposite ends relatively adjustable by means of adjustment screws 61. The lowermost arm 58 has its end extended at 62 and this extended end engages a shoulder 63 on sleeve 44. The uppermost arm 60 has a turned-up extension 64 which carries a roller 65 adapted to ride over the lower peripheral surface of disk 22 and engageable by the spaced projections 26 thereon. During the engagement of roller 65 with the disk surfaces between the projections 26, the clutch members 43 and 44 are in engagement with one another by virtue of the action of spring 46. However, when one of the projections 26 engages the roller 65, the multi-arm bracket 56 is rotated slightly counter-clockwise, as viewed in Fig. 2, thereby moving the clutch member 43 out of engagement with clutch member 42 as illustrated in Fig. 2. Thus, at regular intervals determined by the speed of rotation of disk 22 and the spacing of projections 26 thereon, the clutch members 42 and 43 are temporarily disengaged. This periodic operation of the clutch member serves to rotate the arm 50 counter-clockwise a slight amount each time the clutch is disengaged.

The above-described parts of the tripping mechanism are so constructed that the mechanism is not tripped as long as the tone-arm moves over the record at its normal rate or speed while the stylus is traversing the sound grooves of the record. During such normal movement of the tone-arm, the slight movement of the arm 50 occurring between successive disengagements of the clutch 42-43 is insufficient to actuate the latch member 38. Each time the clutch members are disengaged as above-described, the lower clutch member returns to normal engaged position by virtue of the tension of spring 46. Since the intervals at which the clutch members 42 and 43 are disengaged are fixed by the fixed spacing of projections 26 and the constant speed or rotation of disk 22 driven from the constant speed turntable driving means, the operation of the latch-tripping member 51 is dependent entirely upon the rate of movement of the tone-arm as it traverses a record.

As stated previously, the purpose of the tripping mechanism is to operate the tone-arm lifting device at the end of a record and also to interrupt the playing of a record and lift the tone-arm in the event that the tone-arm moves too rapidly at any time. The operation of the tripping mechanism at the end of a record is brought about when the stylus or needle 7 engages a special groove which causes the tone-arm to move rapidly inward. At such time or in the event that the tone-arm should move laterally too rapidly at any time, the arm 50 is moved sufficiently between successive disengagements of clutch 42-43 to trip latch member 38, thereby permitting arm 19 to move to operative position under the influence of spring 36. This brings the curved edge 66 of cam follower 30 (see Fig. 1) into the path of the shoulder 67 on cam 29, the latter rotating clockwise, as viewed in Fig. 1. The cam follower 30 is thereby caused to move away from stop 32 into engagement with stop 31. Since the element 30 can move no further, 75 the cam 29 causes pivotal movement of arm 19,

bringing the curved end thereof into engagement with arm 13 of the tone-arm-lifting device, as shown in Fig. 3. The cam 29 maintains the arm 19 in its effective position during the movement of the tone-arm to the beginning of a record by means of the arm 20 as above described. After the tone-arm has been thus moved, the cam 29 releases element 30, permitting it to move back against stop 32. The arm 19 is thereby permitted to move back to its latched position out of engagement with the tone-arm-lifting device. Consequently, the parts of the tone-arm-lifting device are restored by the weight of the tone-arm and by gravity to the positions of Fig. 3, the stylus being deposited at the beginning of the record. To limit the counter-clockwise movement of the arm 50, a suitable stop (not shown) may be provided together with a linkage (not shown) to maintain the clutch 42-43 disengaged during the interval when the arm 19 is displaced from its rest position. These elements have not been illustrated since they are well known and are not essential to the present invention.

In order to prevent the trip mechanism from operating at the beginning of a record, there is provided a detent bar or link 68 which has one end pivotally attached to clutch member 42 at 69. The opposite end of bar 68 is slidably retained by guide means 70 on the supporting bracket 28. The bar 68 has a shoulder 71 which engages arm 51 during the first part of a record reproduction and prevents the arm 51 from tripping the latch member 38. Since the bar 68 moves toward the left, as viewed in Fig. 1, during the inward movement of the tone-arm, the shoulder 71 is moved past arm 51 after a predetermined interval and thereafter the latch member 38 may be tripped by arm 51 as described above depending on the rate of movement on the tone-arm. The bar 68 thus prevents objectionable tripping of the mechanism at the beginning of a record in the event that the stylus is moved laterally due to any cause. When the mechanism is tripped and the tone-arm is moved back to the beginning of the record, the bar 68 is returned to its effective position, as shown in Fig. 1.

It will be seen that the invention provides a trip mechanism for an automatic phonograph which is responsive to the speed or rate of movement of the pick-up or reproducer and which by a simple and novel means is prevented from operating during the initial portion of the reproduction. Thus, the invention eliminates undesirable tripping of the mechanism which has been an objectionable characteristic of prior devices.

It will be understood, of course, that the invention may take specific forms other than that illustrated without departing from its scope, as defined by the appended claims.

5 I claim:

1. A stopping mechanism for a phonograph having a pivotally mounted reproducer, said mechanism comprising means for automatically stopping the reproduction of a recording, a movable trip member for actuating said stopping means, said trip member having a normal inoperative position and an operative position to which it is movable from its normal position, means for coupling said trip member to said reproducer so that the reproducer drives said trip member toward its operative position, means for periodically decoupling said last-named means and returning said trip member to its normal position so as to prevent actuation of said stopping means during normal movement of the reproducer, and means for rendering said trip member ineffective during the playing of a part of a recording, said last-named means comprising a movable member adapted in certain positions to prevent the advance of said trip member, and operatively connected to said reproducer eccentrically of the pivot thereof so as to be movable by the motion of the reproducer over the recording.

2. A stopping mechanism for a phonograph having a pivotally mounted reproducer, said mechanism comprising means for automatically stopping the reproduction of a recording, a movable trip member for actuating said stopping means, said trip member having a normal inoperative position and an operative position to which it is movable from its normal position, a clutch comprising driving and driven disks arranged coaxially with the reproducer pivot for coupling said trip member to said reproducer so that the reproducer drives said trip member toward its operative position, means for periodically disengaging said clutch disks and returning said trip member to its normal position so as to prevent actuation of said stopping means during normal movement of the reproducer, and means for rendering said trip member ineffective during the playing of a part of a recording, said last-named means comprising a longitudinally movable bar pivotally connected to the driving clutch disk eccentrically of the reproducer pivot, said bar having a shoulder thereon which engages said trip member during a part of the movement of the bar and thereby prevents the advance of the trip member.

ELMER O. THOMPSON.
